UNITED STATES PATENT OFFICE.

ROBERT E. HENRY, OF PITTSBURGH, PENNSYLVANIA.

PROTECTIVE COVERING FOR BATHTUBS AND METHOD OF UTILIZING THE SAME.

Application filed November 29, 1926. Serial No. 151,525.

My invention relates to protective coverings for bath tubs, lavatories and similar porcelain and enameled plumbing goods.

Considerable difficulty has heretofore been experienced in suitably protecting plumbing fixtures, such as bath tubs, wash bowls and the like, during shipment and installation. The highly finished surfaces of these articles many times become scratched during handling and are also damaged during installation, by reason of plaster, mud and cement falling upon the articles and scratching the surface when being removed therefrom, through workmen dropping their tools into the tubs or standing in them, and from various other causes. Even slight injury reduces the tub to the rank of second quality, and in many cases, causes rejection thereof by the purchaser, with the consequent expense of returning the same to the factory and the shipment of a replacement which may in turn also become damaged.

My invention has for one object the provision of a temporary protective covering for bath tubs and the like, of such form and material that the tub will be adequately protected during shipment and installation, and which will not readily become accidentally detached or torn from the tub.

Another object of my invention is to provide a covering that will not have to be removed from a tub during the plastering-in or tiling-in operation, and which will, nevertheless, adequately protect the tub and not interfere with neatly finishing the tiling structure.

Some of the forms which my invention may take are shown in the accompanying drawing, wherein Figure 1 is a perspective view showing a portion of a cover in place upon the tub after the same has been tiled in, including the means for holding that portion of the cover adjacent to the tiled in edges of the tub in position; Fig. 2 is a view showing a modified form of holding means for the cover; Fig. 3 is a cross sectional view showing one manner in which the outer ends of the holding tapes of Fig. 1, may be held in position; Fig. 4 is a similar view, showing another manner of holding the tapes; Fig. 5 is an end elevational view of a portion of the tub of Fig. 1; Fig. 6 is a plan view of such portion; Fig. 7 is a view

showing the blank from which bath tub covers may be conveniently formed; Fig. 8 is a view showing a third arrangement whereby the cover may be held in place during the tiling-in operation; Fig. 9 is a view taken on the line 9—9 of Fig. 8, and Fig. 10 is a view showing a portion of the cover supporting the displacement, by a plaster coating.

For convenience of illustration, I have shown the cover as employed in connection with bath tubs, but it will be understood that the invention may be utilized in connection with other articles. The cover 11 may be formed of any suitable material, such as crepe paper, which will yield somewhat, to reduce the danger of tearing, as when the cover does not completely fill a corner in the tub. The cover is preferably provided of such size that it will overlap the exposed front wall of the tub and the ends thereof, the outer wall of the tub usually having a glazed finish, and one or both ends of the tub also having a highly polished finish. The cover may end at the rear or unfinished side of the tub any convenient distance. When the tub leaves the factory, the cover can be secured thereto in any suitable manner, and if it is made from a blank represented in Fig. 7, by the numeral 11^a, the corners *b* of the covers when sewed together, will snugly engage the rim of a full recess (3 sides tiled in) tub at the corners thereof, when folded down, although it will ordinarily yield sufficiently to permit turning back thereof, as indicated by the numeral 13 in Fig. 2. It will be understood that the flaps of the blank of Fig. 7, will be sewed or otherwise fastened together at their adjacent edges *c*, so that such blank will have substantially the contour of the inner and outer surface of the tub.

When the tub is to be placed in position, it will be set against a wall 15, as indicated in Figs. 3 and 4, which wall may or may not have been previously plastered. In the drawing, a "scratch" coat of plaster 16 is shown as applied to the lath 17. In any event, the edge 18 of the cover (Figs. 1 and 3) is turned back so as not to be caught between the edge of the tub and the wall, and to permit the tiling or facing plaster to be brought down snugly against the rim 19 of the tub.

While ordinarily the rear edge of the cover

will extend substantially over the back wall of the tub, it is desirable that so much be torn off as will permit the tile setter to work conveniently, and to this end I may weaken or perforate the cover along a line adjacent to the rear rim of the tub so that the tile setter can readily tear away and remove the surplus material.

Strips of tape or string 20 are secured, at 10 their inner ends to the cover, and their outer ends will extend through or over the cover edge 18 and may be tacked to the wall 15, as shown in Fig. 3, or be glued to the back wall of the tub, as shown in Fig. 4. Also, it 15 could be simply caught between the edge of the tub and the wall, or held by weights.

In order to insure that portions of the cover edge 18 will not be turned back so far as to permit the rim of the tub to be 20 damaged, or to allow plaster to fall behind the covering, I show, in Fig. 1, sticks 21, inserted between the tapes 20 and the edge 18. The edge 18 may be conveniently turned back under or over these strips, and 25 the plaster base 22 for the tiles 23 applied, as well as the tiles. The tiles 23 will rest upon the exposed portion of the rear edge 19 of the tub, as shown more clearly in Figs. 1 and 10. These tiles may rest upon the extreme 30 rear edge of the rim 19, or such rim may extend into the plaster for some distance, as indicated in Fig. 3, in which case, the rim may be covered for one-half of its width or more. The tile 23 will extend 35 across the outer portion of the tapes 20, but when the cover is later removed, the tapes can be cut away by undercutting close up to the tile leaving a scarcely noticeable defect in the pointing, which can be readily faced over and will not be nearly so conspicuous as if the rear edge of the cover extended beneath the tile and had to be cut away. The tapes will preferably be of thin, strong material.

40 After the plasterers, painters, plumbers, etc. have completed their work in the bathroom and the house is ready for delivery to the owner, the cover can be removed from the tub and destroyed.

45 In Fig. 2, I show an arrangement whereby means are provided in lieu of the tapes 20 for supporting the rear edge of the cover, such means consisting of a hoop-like member 25, fitting within the tub, and yieldably 50 engaging the same. The member 25 has projections 26 formed integrally therewith for supporting stay rods 27 that may in turn be formed integrally with the connecting bars 26. The members 25, 26 and 27 may 55 be formed of rods or flat strips, as desired, and the stay rods 27 will extend along the rear side, of either or both of the ends of the tub, depending upon whether the tub is tiled in the wall at only one end or at both 60 ends. The edges of the cover will be turned

back from the rods 27 to permit tiling-in as in the case of the rods 21 of Fig. 1.

In Figs. 8 and 9, I show still another form of stay apparatus for holding the rear end portions of the cover in engagement with the rim of the tub. The stays consist of strips 28, preferably of ductile metal and which may be round or flat in cross section, as desired. The strips are placed against the inner surface of the cover and are shown 75 as held in place by strips of paper or other material 29, which may be stitched or otherwise secured to the cover 11. The stays 28 are bent at their upper and lower ends, to conform to the contour of the tub, so that 80 they will more effectively hold the edge of the cover in contact with the rim of the tub.

Referring to Fig. 10, I show still another means for holding the cover in close engagement with that portion of the tub rim 85 which is to be tiled in. This means comprises a coating of cement, plaster of Paris, or similar material 30 which is spread upon a portion of the cover by a brush, or in any other suitable manner, either previous to 90 shipment of the tub from the factory or after the tub reaches the place of installation, and previous to the tiling-in operation. In this case, the free edge 18 of the cover will be 95 preferably untreated, so that it can be more readily turned back upon the stiffened portion, to permit placing of the tiles 23.

100 It will be understood that various other means may be provided for supporting the cover in position at the tiled-in edges of the tub, without departing from the spirit and scope of this invention.

I claim as my invention:—

1. The method of tiling-in rimmed bath 105 tubs having flexible liners provided with tape-like extensions, which comprises securing said tapes to the wall against which the tub is to be tiled, exposing the rim at the edge of the cover, and tiling against the rim.

2. The method of tiling-in bath tubs having 110 liners, which comprises holding a liner in place against one side of the tub by strips whose inner ends are secured to the liner and whose outer ends are secured at a point rearwardly of the tub, and tiling over said 115 strips.

3. The method of tiling-in or plastering 120 in bath tubs having flexible liners, which comprises supporting a liner against displacement at a point adjacent to that at which the tub is to be tiled, and tiling in the tube at a point behind the adjacent edge of said liner.

4. The method of tiling-in or plastering 125 in rimmed bath tubs having liners, which comprises supporting a liner on a tub rim, and on a longitudinal line removed from the outer edge of said rim, and tiling or plastering in said outer edge of the rim.

5. The method which comprises placing a 130

flexible liner in a bath tub, turning back the edge of the liner to expose the tub rim, and tiling in said rim.

6. The method which comprises placing a flexible liner in a bath tub, and providing a line of support for said liner adjacent to one rim of the tub, turning back that portion of

the liner beyond the line of support, to expose the rim of the tub, and tiling in the said rim.

10

In testimony whereof I the said ROBERT E. HENRY have hereunto set my hand.

ROBERT E. HENRY.
